CLAIM

The ornamental design for the punching bag, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a front perspective view of the punching bag.

FIG. 2 is a front view of the punching bag.

FIG. 3 is a rear view of the punching bag.

FIG. 4 is a left view of the punching bag.

FIG. 5 is a right view of the punching bag.

FIG. 6 is a top view of the punching bag; and,

FIG. 7 is a bottom view of the punching bag.
